8 Claims. (Cl. 206—37)

This invention relates to power holding compacts and the like.

Because of the highly competitive nature of the compact case art, a simple and economically constructed, positive and readily operable catch structure has been an important factor therein. Numerous catch structures have been developed over the years for use in such compact cases; however, heretofore, none has completely satisfactorily combined the above discussed desirable features.

Another problem encountered in the compact art for which no completely satisfactory answer has heretofore been found, is the provision of means for removing a spent pressed powder cup from a refillable compact. This problem is particularly vexatious to the user as removal of the spent powder cup in the known compacts often results in powder being spilled onto the person or over the surrounding area.

The principal feature of the instant invention is the provision of new and improved compact means resolving the above indicated problems.

Another feature of the invention is the provision of compact means having new and improved latch means.

A further feature of the invention is the provision of new and improved compact means arranged for removal of a replaceable powder cup therefrom.

Still another feature of the invention is the provision of such compact means having improved means for indicating desirable information.

A still further feature of the invention is the provision of a compact means having new and improved latch means and powder cup removing means co-ordinated to preclude inadvertent removal of the powder cup.

Other features and advantages of the invention will be apparent from the following description taken in connection with the accompanying drawing wherein:

FIG. 1 is a perspective view of a compact embodying the invention;

FIG. 2 is an enlarged, fragmentary front elevation thereof in a closed arrangement;

FIG. 3 is a fragmentary section taken approximately along the line 3—3 of FIG. 2;

FIG. 4 is a fragmentary view looking at the inside of the cover showing the catch means thereof;

FIG. 5 is a fragmentary view looking at the inside of the shell showing the catch means thereof;

FIG. 6 is a bottom view of the compact with a portion of the shell broken away;

FIG. 7 is a vertical diametric section, with the cover in the open position and a portion thereof shown in elevation;

FIG. 8 is a fragmentary view similar to that of FIG. 7 illustrating the removal of the powder cup from the shell;

FIG. 9 is a fragmentary view illustrating a modification of the invention;

FIG. 10 is a fragmentary view illustrating another modification of the invention;

FIG. 11 is an enlarged fragmentary bottom view of a compact means having a modified form of powder cup removal means;

FIG. 12 is a fragmentary vertical section thereof;

FIG. 13 is a fragmentary view illustrating still another modification of the invention;

FIG. 14 is a fragmentary view similar to that of FIG. 13, but with the powder cake in a partially removed disposition;

2

FIG. 15 is an enlarged fragmentary view illustrating yet another modification of the invention; and

FIG. 16 is a fragmentary view illustrating a still further modification of the invention.

5 In the exemplary embodiment of the invention, as disclosed in FIGS. 1 through 8 of the drawings, a compact generally designated 10 is shown to comprise a cup-shaped shell 11 and a complementary cup-shaped cover 12 movably secured to the shell by a hinge means 13. Removably installed in shell 11 is a powder cup 14 holding a cake 15 of pressed powder for free accessibility when the cover is swung upwardly away from the shell.

New and improved means are provided for releasably latching the cover to the shell. The latching means comprises a first catch means 16 formed in a front portion 17 of the peripheral, upstanding wall 18 of shell 11, and a second catch means 19 formed in a front portion 20 of the peripheral depending wall 21 of cover 12.

First catch means 16 is formed integrally with wall portion 17 and includes a first or thumbpiece portion 22 projecting upwardly and outwardly from wall portion 17, a midportion 23 extending from thumbpiece portion 22 inwardly of cover wall portion 20, and a hooked end portion 24 extending outwardly from mid-portion 23.

25 Second catch means 19 comprises an inwardly extending rib 25 defining an inwardly extending shoulder 26 facing away from shell 11 when cover 12 is closed on the shell. Rib 25 extends inwardly beyond the outermost portion of hook end 24 so that when the cover is closed on the shell, end 24 snaps outwardly over rib 25 to latch against shoulder 26. Associated with second catch means 19 is a guide 27 arranged to be engaged by the lateral edges 22a of thumbpiece 22 to preclude undesired lateral movement of wall portion 20 relative to wall portion 17 and, thus, maintain proper alignment of the cover and shell. More specifically, guide 27 comprises an inwardly bowed bridge 27a formed integrally in cover wall portion 20, the end portions 28 of which are spaced slightly greater than the lateral extent of thumbpiece 22.

30 As used herein, the term "inwardly" is defined as in a direction toward the mid-portion of the space defined by the compact shell or cover, the term "outwardly" is defined as away therefrom, and the term "laterally" is defined as in the directions of lateral extent of the wall portions 17 and 20 (to the right or left as seen in FIG. 2).

To release catch means 16 from engagement with shoulder 26 of catch means 19, thumbpiece portion 22 is urged inwardly, as by the user's thumb. To facilitate this releasing action and, at the same time, effectively preclude 35 a tendency to cause lateral movement between the compact shell and cover during the releasing operation, the catch means 16 and 19 are made to have a substantial lateral extent, preferably comparable to the width of a person's thumb. Further, the thumbpiece portion 22 extends substantially above the shell wall 18 providing an improved resilient yieldability to permit the desired disengagement of the catch means.

40 As alluded to briefly above, powder cake 15 is provided in a cup 14 permitting ready removal and replacement thereof in compact 10 as desired. Such replacement may be effected to refill the compact when the powder cake thereof has been spent; or alternatively, a plurality of different powder cakes having different shades or textures may be utilized, one at a time, in a single compact as desired by the user. More specifically, powder cup 14 comprises a cup-shaped member in which powder cake 15 is permanently retained. The powder cup 14 is slightly smaller than shell 11 to permit the cup to be received and fixedly retained therein. To facilitate the removal of the 45 powder cup 14 from shell 11 when desired, the bottom wall 29 of the shell is provided with an opening 29a which is preferably sufficiently large to permit a person's finger

to extend therethrough, as seen in FIG. 8. The portion 30 of the bottom wall 31 of powder cup 14, which is accessible through opening 29a, herein comprises a boss complementary to opening 29a and projecting downwardly from bottom 31 of the powder cup through the opening. As shown in FIG. 3, boss 30 may terminate flush with the outside surface of the shell bottom wall 29; it should be understood, however, that the invention comprehends such cup structures wherein the boss terminates other than flush with said bottom.

Means for indicating desirable information, such as the brand and shade of powder in cup 14, is provided in the form of an indicia element or label 32 secured to the outer surface of boss portion 30 of the cup member. The indicia element is legible at all times, eliminating the necessity of opening the compact in order to obtain information as to the type of powder cake installed therein.

As the user's finger may engage a substantial area of the powder cup, a relatively high frictional retaining force may be employed to secure the cup in shell 11. Thus, inadvertent removal of the cup from the shell, such as occurs in the known refillable compact devices, is effectively precluded. In addition, the catch means 16 assists in the retention of the powder cup in shell 11. As best seen in FIGS. 3, 7 and 8, mid-portion 23 of catch 16 extends inwardly to overlie the forward portion of the powder cup and prevents a separation of the cup from the shell by movement upwardly away from shell bottom wall 29.

FIG. 9 illustrates a modified form of compact 110 in which the side wall of boss portion 130 of the bottom of powder pan 114 is provided with a step 135 which seats on a peripheral portion 136 of the bottom 129 of shell 111, surrounding opening 129a. This interengagement limits the amount by which the center portion of powder pan 114 may be inserted into shell 111, properly positioning the pan in the shell. FIG. 10 illustrates another modified form of compact 210 in which a shell 211 is provided with an upwardly extending flange 237 surrounding an opening 229a and engaging the bottom wall 231 of the powder pan for properly positioning the pan in the shell.

In FIGS. 11 and 12, still another modified form of compact 310 is shown to be provided with a small elongated opening 329a in the bottom 329 of the shell 311 thereof. Opening 329a is juxtaposed to the periphery of bottom wall 329 adjacent hinge 313. As best seen in FIG. 11, opening 329a comprises a circular mid-portion 329b and laterally extending elongated portions 329c. Mid-portion 329b is adapted to permit the passing of a cylindrical element 340 (FIG. 12), such as a pinhead, therethrough for engaging the bottom wall 331 of the powder cup to urge the powder cup upwardly from the shell 311 when desired. Aligned elongated portions 329c are arranged to permit the insertion of a blade element (not shown), such as a nail file or the like, therethrough to effect a similar removal of the powder cup.

In FIGS. 13 and 14, another modified form of compact 410 is shown to be provided with an imperforate shell bottom wall 429 which is bowed outwardly. A pad 441 is secured to bottom wall 429 to extend upwardly therefrom into engagement with the bottom wall 431 of the powder cup. To effect a removal of the powder cup from shell 411, shell bottom wall 429 is pressed inwardly, as by the user's thumb, to the position of FIG. 14.

FIG. 15 illustrates another modification of the invention in which an imperforate bottom wall 529 of a compact 510 is provided with an upstanding annular deformation 542 disposed concentrically of the depending boss portion 530 of the cup member. Deformation 542 provides for increased ease of movement of the mid-portion 543 of the bottom wall 529, facilitating the removal of the powder cup from the shell by the upward urging thereof by the user's thumb.

In FIG. 16, an imperforate bottom wall 629 of a com-

pact 610 is provided with a central upstanding deformation 644. Bottom wall 629 is bowed similarly to bottom wall 429 of compact 410 and deformation 644 functions similarly to pad 441 in effecting the desired movement of the powder cup from the shell when the bottom wall is pressed inwardly.

The disclosed compact means provide improved functioning relative to the latching of the cover to the shell and relative to the replaceability of the powder cakes 10 therein. The cover is positively latched closed merely by swinging it on hinge 13 to the position of FIG. 3 wherein shell catch end 24 is automatically snapped into retaining engagement with cover catch shoulder 26. To open the compact, the user merely presses button portion 22 15 which, by virtue of its substantial lateral extent, readily effects a separation of the catch end 24 from shoulder 26, permitting the cover to be swung upwardly for access to the powder cake 15. An automatic guiding action is effected by the catch means precluding lateral movement 20 thereof during the opening and closing operations and when the compact is closed, preventing twisting or deformation of hinge 13.

The replacement of powder cakes 15 in the compacts 10, 110 and 210 is effected quickly and cleanly by the insertion of the user's finger through the large opening in the shell bottom wall to overcome the frictional retention of the powder cup in the shell and move it upwardly therefrom, as seen in FIG. 8. In compact 310, the removal of the powder cup is effected by readily available means such 30 as a pin or nail file. In compacts 410, 510 and 610, flexing of an imperforate bottom wall of the shell effects the desired removal of the powder cup. The replacement powder cake is installed in each of the disclosed compacts merely by insertion thereof into the shell whereupon 35 the replacement powder cake is retained positively in the compact until desired removal thereof is effected by the user.

While I have shown and described certain embodiments of my invention, it is to be understood that it is capable 40 of many modifications. Changes, therefore, in the construction and arrangement thereof may be made without departing from the spirit and scope of the invention as defined in the appended claims.

I claim:

1. Compact means comprising a shell provided with a peripheral, upstanding wall having a portion defining a first catch means, a cover provided with a peripheral, depending wall aligned and substantially congruent with said shell wall and having a portion defining a second, complementary catch means, one of said catch means comprising an inwardly extending rib, and the other of said catch means projecting to inwardly of said rib and having a hooked end snapping outwardly over said rib when the cover is closed on said shell, and means associated with said one of said catch means to define side guides extending from the end of the wall provided with said one catch means and engageable by the other catch means to guide said other catch means to the locking position and preclude undesired movement of the other catch means in the directions of lateral extent of said wall portions.

2. Compact means comprising a shell provided with a peripheral, upstanding wall having a portion defining a first catch means, and a cover provided with a peripheral, depending wall aligned and substantially congruent with said shell wall and having a portion defining a second, complementary catch means, one of said catch means comprising a flat shoulder facing away from the upper end of the shell wall when the cover is closed on the shell, and the other of said catch means projecting to inwardly 65 of said shoulder and having a hooked end snapping outwardly over said shoulder when the cover is closed on said shell.

3. Compact means comprising a shell provided with a peripheral, upstanding wall having a portion defining a first catch means, and a cover provided with a peripheral,

depending wall aligned and substantially congruent with said shell wall and having a portion defining a second, complementary catch means, one of said catch means comprising a flat shoulder facing away from the upper end of the shell wall when the cover is closed on the shell, and the other of said catch means having a first portion extending outwardly from the wall, a thumbpiece extending upwardly from the first portion, a mid-portion extending from said thumbpiece inwardly of said shoulder, and a hooked end portion extending outwardly from said mid-portion and snapping over said shoulder when the cover is closed on said shell.

4. Compact means comprising a shell provided with a peripheral, upstanding wall having a portion defining a first catch means, a cover provided with a peripheral, depending wall aligned and substantially congruent with said shell wall and having a portion defining a second, complementary catch means, one of said catch means comprising a shoulder, the other of said catch means comprising a projection extending inwardly of said one catch means and having a hooked end snapping outwardly over said shoulder when the cover is closed on said shell, and a guide adjacent said one of said catch means comprising an inwardly bowed bridge having ends engageable by the opposite sides of the other catch means to preclude undesired movement of the other catch means in the directions of lateral extent of said wall portions.

5. Compact means comprising a shell provided with a peripheral, upstanding wall having a portion defining a first catch means, and a cover provided with a peripheral, depending wall aligned and substantially congruent with said shell wall and having a portion defining a second, complementary catch means, one of said catch means comprising an inwardly extending rib, and the other of said catch means comprising a projection having a resiliency greater than that of the wall on which it is provided extending to inwardly of said rib and having a hooked end slideable against said rib to snap outwardly over said rib when the cover is closed on said shell, said other of said catch means further including means for manually moving said hooked end inwardly of said shoulder when desired to permit disengagement of said catch means.

6. Compact means comprising a shell provided with a peripheral, upstanding wall having a portion defining a first catch means, a cover provided with a peripheral, depending wall aligned and substantially congruent with said shell wall and having a portion defining a second, complementary catch means, one of said catch means comprising

an inwardly extending shoulder, and the other of said catch means projecting to inwardly of said shoulder and having a hooked end snapping outwardly over said shoulder when the cover is closed on said shell, and a thumbpiece formed integrally with said other of said catch means for moving the same inwardly of the shoulder when desired, each of said shoulder, hooked end and thumbpiece having a lateral extent substantially equal to the width of a person's thumb.

- 5 7. Compact means comprising a shell provided with a peripheral, upstanding wall having a portion defining a first catch means, a cover provided with a peripheral, depending wall aligned with said shell wall and having a portion defining a second, complementary catch means, 15 one of said catch means comprising an inwardly extending rib, and the other of said catch means projecting to beyond the end of the wall on which it is carried and to inwardly of said rib and having a hooked end snapping outwardly over said rib when the cover is closed on said 20 shell, means associated with said one of said catch means to define side guides engageable by the other catch means to preclude undesired movement of the other catch means in the directions of lateral extent of said wall portions, said shell having an opening; a powder pan removably retained in the shell and having a portion projecting into said opening movable through said opening by a person's finger to remove the pan from said shell.

- 25 8. Compact means comprising: a cup-shaped shell having an opening in the bottom thereof sufficiently large to permit a person's finger to extend thereto, said shell being provided with an upwardly extending flange surrounding said opening; and a powder pan removably retained in said shell and having a bottom juxtaposed to the shell bottom and including a portion complementary to and projecting through said opening, said portion being movable through said opening by the person's finger to remove the pan from said shell, said shell and pan having interengaging surfaces which limit the depth of insertion of said pan bottom projecting portion into said opening.
